CAR ROOF

Charles David Bonsall, Pittsburgh, Pa., assignor
to P. H. Murphy Company, New Kensington,
Pa., a Corporation of Pennsylvania

Application April 30, 1931. Serial No. 533,954

15 Claims. (Cl. 108—5.4)

This invention relates to car roofs of the all-steel riveted-up type, wherein the roof sheets extend from side plate to side plate and are spaced apart along their adjacent margins which are connected by weatherproofing seam caps that function as hollow exterior carlines.

The principal object of the present invention is to devise a car roof of the above type which will be cheaper, stronger and more rigid than previous car roofs having the same weight of metal. Another object is to prevent any water that may enter the seam caps from reaching the interior of the car. The invention consists in the car roof, and in the construction, combinations and arrangements of parts hereinafter described and claimed.

In the accompanying drawings, which form part of this specification and wherein like symbols refer to like parts wherever they occur,

20 Fig. 1 is a plan view of a portion of a car roof embodying my invention.

Fig. 2 is a vertical transverse cross-section through the roof on the line 2—2 in Fig. 1.

25 Fig. 3 is a vertical transverse cross-section through the ridge portion of the roof, the section being taken along one of the seams on the line 3—3 in Fig. 1.

Fig. 4 is a vertical cross-section through the roof at the eaves, the section being taken through one of the seams on the line 4—4 in Fig. 1.

30 Fig. 5 is a vertical cross-section through one of the seams at the ridge on the line 5—5 in Fig. 1.

Fig. 6 is a vertical cross-section through a seam of modified construction.

35 Fig. 7 is a vertical section on the line 7—7 in Fig. 6; and

Fig. 8 is a vertical cross-section through another seam of modified form.

The present construction comprises pitched metal roof sheets A that extend from side plate B to side plate B of the car. The side plates B are preferably of substantially Z-shaped cross-section and are arranged with the inner flange 1 upstanding and provided at its top with an integral flange 2 that extends inwardly at an angle conforming to the pitch of the roof and serves as a support for the eaves end portions of the roof sheets A to rest upon. The roof sheets

40 A are provided with depending eaves flanges 3 that overlap and are rigidly secured to the upstanding inner flanges 1 of the side plates by horizontal rivets 4. The roof sheets are preferably formed with raised side marginal panels 5 that terminate at the side edges of the sheets in upstanding seam flanges 6.

The roof sheets A are spaced apart along their adjacent side edges which are connected by weatherproofing seam caps C of substantially inverted channel-shaped cross-section that extend from side plate to side plate and function after the manner of hollow exterior carlines. The seam caps C straddle the spaced adjacent side marginal flanges 6 of adjacent roof sheets and have their side walls rigidly secured respectively to said flanges by rivets 7; and said seam caps are provided at the lower edges of their side walls with outstanding base flanges 8 that rest respectively upon the raised adjacent side marginal panels 5 of adjacent roof sheets. The seam caps are curved downwardly at their ends 60 to close the same and are provided with depending end flanges 9 that overhang the adjacent end portions of the depending eaves flanges 3 of adjacent roof sheets and are rigidly secured thereto and to the side plates by rivets 4.

65 The adjacent side marginal flanges 6 of adjacent roof sheets are held in contact throughout their length with the side walls of the inverted channel-shaped seam caps C by means of inverted channel-shaped strips 10 that are located within 70 said seam caps between the sheet flanges straddled thereby. These strips extend longitudinally of the seam caps substantially from end to end thereof and have their depending side flanges rigidly secured flatwise to the respective sheet flanges by 75 rows of rivets 7 that secure the latter to the respective side walls of said seam caps. It is a very important advantage of the strip 10 that it reinforces the side marginal flanges of the roof sheets and the side walls of the seam caps against 80 buckling and thereby contributes greatly to the strength and waterproofing qualities of the roof. Another advantage of the reinforcing and stiffening strip is that it permits a wider spacing of the rivets 7 without danger of the sheet flanges 85 buckling between rivets and thus permitting water to pass over said flanges into said caps.

85 A combined drain and sheet supporting strip 11 extends longitudinally of each of the seam caps and the adjacent side marginal portions of the 90 adjacent roof sheets straddled thereby and has depending end flanges 12 that overlap and are rigidly secured to the upstanding inner flanges 1 of the side plates B by the rivets 4 that secure 95 the eaves ends of the roof sheets and the seam cap to said side plates. The strip 11 is wider than the space between adjacent roof sheets and has its marginal portion struck up beneath the raised side marginal panels 5 of said roof sheets to 100 form side marginal raised flanges 11a for the 105

roof sheets to rest upon and a longitudinal drain channel 13 for carrying away water that may get into the seam cap. The strip 11 is suspended from the seam cap C preferably by means of bolts 14 that are carried by said strip and extend downwardly through holes provided therefor in upstanding bosses 15 formed in the gutter 13 of said strip. The bolts 14 are provided with nuts 16 which, when tightened, cause the strip 11 to be drawn upwardly against the underside of adjacent roof sheets to firmly clamp the raised side marginal panels 5 thereof against the undersides of the base flanges 8 of the seam cap C.

The roof is provided with a longitudinal running board comprising sections 17 located between adjacent seam caps with their upper surfaces disposed substantially at the level of the highest points of the seam caps. The end portions of adjacent running board sections 17 are supported on running board saddles 18 fixed to the seam caps located therebetween. Each of said running board saddles comprises an inverted channel-shaped portion that straddles the seam cap and is riveted thereto and is provided at the lower edges of its side walls with outstanding base flanges 19 that serve as supports for the adjacent end portions of adjacent running board sections which are rigidly secured to said flanges by bolts 20. By this arrangement, the sections of the running board are located between the seam caps instead of extending across the tops thereof and thus permit the outside height of the car to be reduced without decreasing the headroom thereof or the headroom of the car to be increased without increasing the outside height. These running board sections also serve as struts for preventing bowing of the seam caps longitudinally of the car.

In the modified construction shown in Figs. 6 and 7, a load-lifting beam 21 is located beneath the roof sheets and is held in place by means of a bolt 14a suspended from the reinforcing strip 10. In this construction, the load lifting beam 21 is located beneath the strip 11, and the bolt 14a extends through said strip and said beam and is provided at its lower end with a nut 16a, which serves to hold said beam in place and to force the raised side marginal flanges 11a of said strip against the undersides of the side marginal sheet panels 5 and thus hold them in contact with the base flanges 8 of the seam cap.

In the modification shown in Fig. 8, the combined clamp and drain strip 11 is dispensed with and the adjacent side marginal seam flanges of adjacent roof sheets have their upper portions bent inwardly towards each other so as to overhang the reinforcing strip 10a, which has a depressed middle portion 13a that serves as a drain channel for carrying off any water that may be forced over the top of the sheet flanges onto said strip.

The hereinbefore described roof construction has the important advantage that it is stronger and more durable and rigid and can be produced more cheaply than previous roofs of the same type having the same weight of metal; and it has the important additional advantages of preventing water that may enter the seam caps from reaching the interior of the car and of preventing the exposure of the rivets 7 to the interior of the car.

Obviously, the hereinbefore described construction admits of considerable modification without departing from the invention. Therefore, I do not

wish to be limited to the precise details of construction shown and described.

What I claim is:

1. A car roof comprising roof sheets extending from side plate to side plate and spaced apart along their adjacent margins which are provided with upstanding flanges, flat-topped inverted channel-shaped carlines straddling the spaced side flanges of adjacent roof sheets, and horizontally disposed members located within said carlines between the spaced roof sheet flanges straddled thereby and rigidly secured to said flanges and to the side walls of said carlines. 80

2. A car roof comprising roof sheets extending from side plate to side plate and spaced apart along their adjacent margins which are provided with upstanding flanges, flat-topped inverted channel-shaped seam caps straddling the spaced side flanges of adjacent roof sheets, inverted channel-shaped members located within said seam caps 85 between the spaced roof sheet flanges straddled thereby, and means for rigidly securing said flanges and said members together and to the respective walls of said seam caps. 90

3. A car roof comprising roof sheets spaced 100 apart along their adjacent margins which are provided with upstanding flanges, inverted channel-shaped seam caps straddling the spaced side flanges of adjacent roof sheets, inverted channel-shaped members located within said seam caps 105 and extending substantially from end to end thereof between the spaced roof sheet flanges straddled thereby, and rivets extending through and rigidly securing the side flanges of said members and said roof sheet flanges together and to the respective sides of said seam caps. 110

4. A car roof comprising roof sheets extending from side plate to side plate and spaced apart along their adjacent margins which are provided with upstanding flanges, inverted channel-shaped 115 seam caps straddling the spaced side flanges of adjacent roof sheets, and members located within said seam caps between the spaced roof sheet flanges straddled thereby for holding the latter in contact with the side walls of the seam caps, said members comprising inverted channels located between the side flanges of adjacent sheets with their side flanges secured thereto and to the side walls of said seam caps. 120

5. A car roof comprising roof sheets extending 125 from side plate to side plate and spaced apart along their adjacent margins which are provided with upstanding flanges, inverted channel-shaped seam caps straddling the spaced side flanges of adjacent roof sheets, members located within said seam caps between the spaced roof sheet flanges straddled thereby for holding the latter in contact with the side walls of the seam caps, and strips suspended from said members and extending substantially the width of the car with their side marginal portions extending beneath adjacent sheets for supporting the latter substantially throughout their length. 130

6. A car roof comprising roof sheets extending 140 from side plate to side plate and spaced apart along their adjacent margins which are provided with upstanding flanges, inverted channel-shaped seam caps straddling the spaced side flanges of adjacent roof sheets, members located within said seam caps between the spaced roof sheet flanges straddled thereby for holding the latter in contact with the side walls of the seam caps, said seam caps having outstanding base flanges, and strips suspended from said members and extending sub- 145 150

- stantially the width of the car with their side marginal portions extending beneath adjacent sheets for supporting the latter beneath said base flanges continuously.
- 5 7. A car roof comprising roof sheets extending from side plate to side plate and having raised side marginal panels that terminate at the side edges of said sheets in upstanding flanges, said sheets being spaced apart along their adjacent side edges, inverted channel-shaped seam caps straddling the spaced side flanges of adjacent roof sheets and having outstanding base flanges resting on the raised side marginal panels thereof, members located within said seam caps between the spaced roof sheet flanges straddled thereby, means for rigidly securing said members to said roof sheet flanges and to the sides of said seam caps, and strips suspended from said members with their side marginal portions offset upwardly and extending beneath the raised side marginal panels of adjacent sheets for supporting said panels beneath the base flanges of said seam caps substantially throughout the length thereof. 80
- 10 8. A car roof comprising roof sheets extending from side plate to side plate and spaced apart along their adjacent margins which are provided with upstanding flanges, inverted channel-shaped seam caps straddling the spaced side flanges of adjacent roof sheets, members located within said seam caps between the spaced roof sheet flanges straddled thereby for holding the latter in contact with the side walls of the seam caps, said seam caps having outstanding base flanges, and strips suspended from said members with their side marginal portions extending beneath adjacent sheets for supporting the latter beneath said base flanges, said strips extending from side plate to side plate and being provided with longitudinal drain channels for carrying off any water that may enter the seam caps. 85
- 15 9. A car roof comprising roof sheets extending from side plate to side plate and spaced apart along their adjacent margins which are provided with upstanding flanges, inverted channel-shaped seam caps straddling adjacent side marginal flanges of adjacent sheets, an inverted channel-shaped reinforcing strip located within each of said seam caps between the adjacent sheet flanges straddled thereby, means for rigidly securing the respective side flanges of said reinforcing strip to the roof sheet flanges and to the side walls of the seam cap, and a load lifting beam suspended from said reinforcing strip. 90
- 20 10. A car roof comprising roof sheets extending from side plate to side plate and spaced apart along their adjacent margins which are provided with upstanding flanges, inverted channel-shaped seam caps straddling adjacent side marginal flanges of adjacent sheets, an inverted channel-shaped reinforcing strip located within each of said seam caps between the adjacent sheet flanges straddled thereby, means for rigidly securing the side flanges of said reinforcing strip to the roof sheet flanges and to the side walls of the seam cap, a load lifting beam suspended from said reinforcing member, and a strip resting on said beam and closing the channel in said seam cap. 95
- 25 11. A car roof comprising roof sheets extending from side plate to side plate and spaced apart along their adjacent margins which are provided with upstanding flanges, inverted channel-shaped seam caps straddling the adjacent side marginal flanges of adjacent sheets, an inverted channel-shaped reinforcing strip located within each of said seam caps between the adjacent sheet flanges straddled thereby, means for rigidly securing the side flanges of said reinforcing strip to the roof sheet flanges and to the side walls of the seam cap, a load lifting beam suspended from said beam and closing the channel in said seam cap, and a strip resting on said beam and closing the channel in said seam cap. 100
- 30 12. A car roof comprising roof sheets extending from side plate to side plate and spaced apart along their adjacent margins which are provided with upstanding flanges, seam caps straddling the adjacent flanges of adjacent sheets, a member of substantially channel-shaped section located within said seam cap between the sheet flanges straddled thereby, and means for securing the side flanges of said member to the sheet flanges and the latter to the side walls of the seam caps, said sheet flanges having laterally bent upper portions that overhang said reinforcing member. 105
- 35 13. A car roof comprising roof sheets extending from side plate to side plate and spaced apart along their adjacent margins which are provided with upstanding flanges, seam caps straddling the adjacent flanges of adjacent sheets, a member of substantially channel-shaped section located within said seam cap between the sheet flanges straddled thereby, and means for securing the side flanges of said member to the sheet flanges and the latter to the side walls of the seam caps, said sheet flanges having laterally extending upper portions that overhang said reinforcing member, the web of said channel-shaped reinforcing member being provided with a longitudinally extending trough. 110
- 40 14. A car roof comprising roof sheets extending from side plate to side plate, flat-topped seam caps connecting the adjacent side margins of adjacent sheets, running board saddles of substantially inverted channel-shaped cross-section straddling said seam caps and riveted to the tops thereof and provided at the lower edges of their side walls with outstanding base flanges, and a running board comprising sections located between adjacent running board saddles, the adjacent end portions of said running board sections being supported on the base flanges of the running board saddle located therebetween. 115
- 45 15. A car roof comprising roof sheets extending from side plate to side plate, flat-topped seam caps connecting the adjacent side margins of adjacent sheets, running board saddles of substantially inverted channel-shaped cross-section straddling said seam caps and riveted to the tops thereof and provided at the lower edges of their side walls with outstanding base flanges, and a running board comprising sections located between adjacent running board saddles, the adjacent end portions of said running board sections being supported on the base flanges of the running board saddle located therebetween with their upper surfaces disposed substantially at the level of the highest points of said seam caps. 120
- 50 16. A car roof comprising roof sheets extending from side plate to side plate, flat-topped seam caps connecting the adjacent side margins of adjacent sheets, running board saddles of substantially inverted channel-shaped cross-section straddling said seam caps and riveted to the tops thereof and provided at the lower edges of their side walls with outstanding base flanges, and a running board comprising sections located between adjacent running board saddles, the adjacent end portions of said running board sections being supported on the base flanges of the running board saddle located therebetween with their upper surfaces disposed substantially at the level of the highest points of said seam caps. 125
- 55 17. A car roof comprising roof sheets extending from side plate to side plate, flat-topped seam caps connecting the adjacent side margins of adjacent sheets, running board saddles of substantially inverted channel-shaped cross-section straddling said seam caps and riveted to the tops thereof and provided at the lower edges of their side walls with outstanding base flanges, and a running board comprising sections located between adjacent running board saddles, the adjacent end portions of said running board sections being supported on the base flanges of the running board saddle located therebetween with their upper surfaces disposed substantially at the level of the highest points of said seam caps. 130
- 60 18. A car roof comprising roof sheets extending from side plate to side plate, flat-topped seam caps connecting the adjacent side margins of adjacent sheets, running board saddles of substantially inverted channel-shaped cross-section straddling said seam caps and riveted to the tops thereof and provided at the lower edges of their side walls with outstanding base flanges, and a running board comprising sections located between adjacent running board saddles, the adjacent end portions of said running board sections being supported on the base flanges of the running board saddle located therebetween with their upper surfaces disposed substantially at the level of the highest points of said seam caps. 135
- 65 19. A car roof comprising roof sheets extending from side plate to side plate, flat-topped seam caps connecting the adjacent side margins of adjacent sheets, running board saddles of substantially inverted channel-shaped cross-section straddling said seam caps and riveted to the tops thereof and provided at the lower edges of their side walls with outstanding base flanges, and a running board comprising sections located between adjacent running board saddles, the adjacent end portions of said running board sections being supported on the base flanges of the running board saddle located therebetween with their upper surfaces disposed substantially at the level of the highest points of said seam caps. 140
- 70 20. A car roof comprising roof sheets extending from side plate to side plate and spaced apart along their adjacent margins which are provided with upstanding flanges, inverted channel-shaped

CHARLES DAVID BONSALL.
